UNITED STATES PATENT OFFICE.

FREDERICK K. FISH, JR., OF SAN FRANCISCO, CALIFORNIA.

PROCESS AND APPARATUS FOR MAKING PULP FROM FIBROUS MATERIAL.

Application filed July 14, 1925, Serial No. 43,595. Renewed May 24, 1927.

This invention relates to a process and apparatus for making pulp from fibrous material and is particularly directed to the circulating of the medium used for the treatment of the material in a digester.

There are many known processes for the production of pulp by the treatment of fibrous material in a digester with various types of cooking liquor, and this invention is applicable to many or all of them but particularly to the sulphite process in which the SO_2 gas and solvent volatile extractives, which are liberated from the material under treatment and form the cooking liquor and collect in the space above the cooking liquor, are removed from the digester, cooled and separated, and are of no further use in the cook.

The chief object of this invention is to provide a process and apparatus for bringing the cooking liquor, preferably mixed with gases and volatile substances which accumulate above the liquor and material under treatment, into intimate and continuously or periodically renewed contact with the material in the digester in the same cook.

A further object is to provide a process and means for continuously or periodically withdrawing a portion of the treating medium from the upper part of the digester and returning it to the lower part of the digester to cause circulation therein.

The invention will best be understood by reference to the accompanying drawing, in which a preferred form of the apparatus is shown in elevation with a portion in section.

In the drawing, 1 represents a digester of the usual type. The lower end of a pipe 2 containing a valve 3 is connected to the bottom conical portion of the digester at a tangent to the surface of this portion of the digester. A steam ejector 4 of any suitable type is connected to the upper end of the pipe 2 and the pipe 5 containing the valve 6 connects the ejector with the digester at a point below the liquor level therein. A screen 7 prevents the admission of the fibrous material to the pipe 5. The space in the digester above the charge and liquor level is connected with the pipe 2, at a point below the ejector, by means of a pipe 8 having a valve 9 and perforated screen 10. Steam under pressure is admitted to the ejector by means of the connection 11.

In the operation of my invention circulation of the liquor, alone or mixed, with the

gases and volatile extractives contained in the space above the liquor in the digester, is effected continuously or periodically as desired. To circulate the liquor alone, steam 60 is admitted to the ejector and the valves 6 and 3 are opened whereby liquor is withdrawn from the upper part of the digester, after it has penetrated through the charge of material, and is forced through the pipe 65 2 into the lower conical part of the digester. The liquor leaving the pipe 2 is given a swirling upward motion owing to the manner in which the pipe enters the lower conical portion of the digester and this upward circulation agitates the charge and brings the liquor into renewed and intimate contact with the particles of material under treatment to remove the encrusting material and liberate the fiber.

When it is desired to circulate the gases and volatile solvent extractives from the space in the digester above the material, the valve 9 is opened and these gases and vapors are drawn from the digester and forced into pipe 2 by the steam from the ejector being there mixed with the withdrawn liquor and again returned to the digester in the manner specified.

Moreover, it may sometimes be desirable to circulate only the gases and volatile solvent extractives from the top of the digester, and this is accomplished with valve 6 closed and valve 9 and the rest of the circuit open.

In the process of making pulp it is of importance that the treating liquor be intimately in contact not only with the material, but with the interior of the material. While it is true the material is submerged in the liquor, the fact remains that the gases, vapors and the stronger part of the liquor and the extractives from the wood rise to the top of the digester. In many instances in known processes the accumulation at the top of the digester is blown off to the atmosphere, but I have discovered that this is not only a waste, but it weakens the liquor, and the benefit of the solvent extractives in various forms for enriching the liquor is lost. I have also discovered that it is possible to save the vapors and extractives from the chips or the like, and so introduce them to the liquor as to materially enrich the latter to better and more quickly act on the chips in the process of digesting or cooking the pulp. With this end in view it is evident that by the

employment of the injector the gases, vapors or liquor at the top of the digester can be withdrawn and introduced to the bottom of the body of liquor and again act on the

- 5 material in the digester. The gases and liquor from the top of the digester are intermixed with the solvent extractives liberated from the chips, which through action 10 or reaction, whether chemical or physical, with the reagent employed, acts materially to shorten the process and is less expensive than processes now in use. The swirling action of the liquor at the bottom of the 15 digester and the ebullition of the liquor creates agitation in the digester, with the result that the liquor impregnates the chips and complete treatment of the constituents thereof is assured.

I claim:

- 20 1. The process of making pulp from fibrous material in a digester, consisting in cooking the material in a heated liquor under pressure and with a space above the body of said liquor, withdrawing gases and volatile extractives from said space and liquor from the upper portion of the body of liquor in the digester by means of steam under pressure, mixing the gases and volatile extractives with the withdrawn liquor and returning the mixture to the lower portion of the digester for use in the same cook.
- 25 2. The process of making pulp from fibrous material in a digester, consisting in cooking the material in a heated liquor under pressure, withdrawing by means of steam under pressure, a portion of the liquor from the upper part of the digester, returning said portion of liquor to the lower part 30 of the digester and imparting to said liquor a swirling motion within the digester.
- 35 3. The process of making pulp from fibrous material as claimed in claim 1, wherein the circulation of gases, volatile extractives and liquor is intermittent in order to

produce a periodically renewed intimate contact between the charge of fibrous material and the treating medium. 45

4. The process of making pulp as claimed in claim 1, wherein a swirling motion is imparted to the mixture of gases and liquor 50 returned to the lower conical portion of the digester in order to agitate the charge of material and produce renewed contact between the particles of the material and the treating medium. 55

5. An apparatus for making pulp from fibrous material, consisting of a digester in combination with an ejector adapted to remove gases, volatile extractives, and liquor from the upper portion of the digester and 60 return the same thoroughly mixed to the lower portion of said digester.

6. An apparatus as defined in claim 5, having means for imparting to the liquor returned to the lower conical portion of the 65 digester a swirling motion.

7. An apparatus for making pulp from fibrous material, consisting of a digester, an external connection between the upper and lower portions of said digester, a steam 70 ejector in said connection, the upper end of said connection having two branches, one connected with said digester at a point below the liquor level therein and the other at a point above the said liquor level and 75 the lower end of said connection being adapted to discharge liquor flowing therethrough at a tangent to the internal surface of the lower conical portion of said digester. 80

8. An apparatus as defined in claim 7, wherein the second mentioned branch pipe is joined to the external connection at a point below the union with the first mentioned branch pipe. 85

In testimony whereof I affix my signature.

FREDERICK K. FISH, JR.
